(57) **CLAIM**

The ornamental design for a novel flash drive shaped as a golf ball, as shown and described.

DESCRIPTION

FIG. 1 is an upper perspective view of a golf ball shaped flash drive showing the design;

FIG. 2 is a lower perspective view of the flash drive showing the design;

FIG. 3 is a front, rear, left and right side view of the flash drive shown in FIG. 1;

FIG. 4 is a top view of the flash drive shown in FIG. 1;

FIG. 5 is a bottom view of the flash drive shown in FIG. 1;

FIG. 6 is an exploded perspective view of the flash drive shown in FIG. 1;

FIG. 7 is a perspective view of the flash drive shown in FIG. 1 with an upper hemisphere removed for ease of illustration; and,

FIG. 8 is another exploded view of the flash drive shown in FIG. 1 wherein the connector portion is inserted in an alternate position with the cord removed for ease of illustration.
